W. I. STIMPSON

FEELER MECHANISM FOR LOOMS

Filed April 7, 1922

UNITED STATES PATENT OFFICE.

WALLACE I. STIMPSON, OF HOPEDALE, MASSACHUSETTS, ASSIGNOR TO DRAPER CORPORATION, OF HOPEDALE, MASSACHUSETTS, A CORPORATION OF MAINE

FEELER MECHANISM FOR LOOMS.

Application filed April 7, 1922. Serial No. 550,471.

To all whom it may concern:

Be it known that I, WALLACE I. STIMPSON, a citizen of the United States, residing at Hopedale, in the county of Worcester and State of Massachusetts, have invented an Improvement in Feeler Mechanisms for Looms, of which the following description, in connection with the accompanying drawings, is a specification, like characters on the drawings representing like parts.

This invention relates to feeler mechanisms for looms.

In that type of feeler mechanism now generally known as the "side swipe," the feeler is mounted for movement in a direction longitudinally of the shuttle and along the filling carrier or bobbin when the filling is substantially exhausted on a detecting beat. The surface of the bobbins or carriers on which the filling or weft thread is wound becomes more or less injured during continued use and the surface of the bobbin or carrier often becomes sticky due to the accumulation of grease and dirt or other foreign substance. Under such conditions the ready response of the feeler to a condition of substantial exhaustion of filling fails to be secured, because the feeler will stick or adhere to the surface of the filling carrier or bobbin and fail to partake of its side swipe movement longitudinally of the filling carrier. Should this defective response of the feeler to substantial exhaustion of filling take place defective cloth is liable to be produced by the omission or partial omission of one or more picks in the shed.

Where the surface of the bobbin has become sticky or roughened or otherwise fails to present a surface of a character over which the feeler will readily slip or slide, the loom will continue to operate with the old filling carrier until complete exhaustion of the filling and such defective operation will be reflected in the finished cloth. In some kinds of cloth this becomes of very great importance, and one of the purposes of the present invention is to provide a feeler mechanism of the side swipe type wherein the feeler will be engaged by an inclined or stepped surface on the bobbin itself when the filling is substantially exhausted on a detecting beat and under the forward pressure of such inclined surface

of the bobbin all liability of the feeler to hesitate or fail to slip along the filling carrier is avoided.

In that type of side swipe feeler mechanism in which the feeler is given movement longitudinally of the shuttle to call a change by frontward pressure of the filling carrier or bobbin upon the feeler, the objections frequently encountered, as above outlined, become more manifest because the pressure of the bobbin surface against the feeler is more liable to emphasize the holding effect of the surface of the bobbin than where the feeler is given its side swipe movement through some other source of power.

An important feature of the present invention therefore consists of a feeler mechanism of the side swipe type in which the feeler is given its side swipe movement in a direction longitudinally of the shuttle by the impact pressure of an inclined surface along the filling carrier or bobbin when the filling is substantially exhausted on a detecting beat, and in the embodiment of the invention as shown by the drawings here-with, the feeler is of the inclined type and the filling carrier or bobbin has its inclined surface formed of stepped portions which gradually become smaller towards the tip end of the bobbin. In some cases, however, of course the inclined surface of the bobbin or carrier may be otherwise formed and the feeler itself may not be extended in an inclined direction towards the lay, but in either case, however, the main essential is that an inclined surface on the bobbin shall become exposed for engagement with the feeler to cause its movement longitudinally of the shuttle when the filling is substantially exhausted on a detecting beat.

In the drawings:

Fig. 1 is a perspective view showing a train of mechanism between the feeler and the replenishing mechanism for effecting replenishment of filling;

Fig. 2 is a plan view showing the feeler mechanism and the action of parts when, on a detecting beat, a working supply of filling is present in the shuttle; and

Fig. 3 is a view similar to that of Fig. 2 showing the feeler being displaced longitudinally along the bobbin by a frontward pressure of the inclined or stepped surface

on the bobbin when the filling is substantially exhausted on a detecting beat.

The replenishing mechanism whereby a fresh supply of filling is furnished when that in the active shuttle has become substantially exhausted, is not illustrated herein, because such mechanism is now well understood in the art and the details thereof form no part of the present invention. Likewise the train of mechanism between the feeler mechanism and the replenishing mechanism may be of any usual type well known in the art and one form thereof is shown by Fig. 1 in sufficient detail to make the operation of the present invention clearly understood.

The loom frame 1 has secured thereto the brackets 2 one at each side of the loom for supporting the usual transverse or rock shaft 3 which controls the operative and inoperative condition of the replenishing mechanism.

Rising from the rock shaft 3 is the arm 4 to which is pivotally connected at 5 the actuator 6, which in the present instance has a foot portion 7 resting upon the top portion of the loom frame. Pivotally connected to the actuator 6 at 8 is the arm 9 the end 10 of which is normally out of the path of movement of the operating member 11 which may be the usual weft hammer or cam follower, or if desired a part-connected thereto. The arm 9 has a finger 12 which overlies the horizontal arm 13 of the bell crank lever 35 pivoted at 14 to the stand 15 which may be secured at 16 to a lug arising from the loom frame. The arm 17 of the bell crank is connected by a transmitter 18 to a slide 19 which is controlled by the feeler, the construction being such that should the feeler, to be more fully described, be given its side swipe movement it will act through the train of mechanism described to place the end 10 of the arm 9 in position to be actuated by the operating member 11 to effect replenishment of filling in the usual manner.

The feeler stand 20 has the rear bearing portion 21 in which is mounted the slide 19 through which the feeler 22 extends. The opening 23 in the slide 19 through which the feeler extends is of a size to permit the feeler to have its limited or normal forward and swinging movement when feeling for the working amount of filling in the shuttle on a detecting beat without causing movement of the slide 19. The feeler 22 is extended frontwardly and has its front stem portion 24 extended through the swivel bearing 25 mounted between the bracket 26 and the top of the feeler stand 20. Between the swivel bearing 25 and the bridge 27 secured to the feeler is a spring 28 which normally acts to move the feeler rearwardly into its feeling position.

The feeler stand 20 is provided with an

opening 29 through which passes the securing bolt 30 whereby the feeler stand may be secured in adjusted position on the loom frame or upon an extension of the shipper stand.

The feeler 22 in the present instance of the invention is of the inclined type, that is it enters the shuttle in a direction inclined to the longitudinal axis thereof on a detecting beat and when the filling is substantially exhausted the feeler is given its side swipe movement longitudinally of the filling carrier or bobbin in the shuttle by the forward pressure of the filling carrier or bobbin as the lay beats up. The character of the feeler mechanism and connected parts may be of the same general construction as that shown and described in the patent to Edward S. Stimpson, No. 1,309,226, dated July 8, 1919.

The lay 31 carries the usual shuttle box 32 having an opening 33 in its front wall through which the feeler may enter the shuttle. The shuttle 34 is also provided with an opening 35 in its front wall, the construction being such that when the shuttle is properly boxed and the lay beats up the feeler 22 may pass through the openings 33 and 35 in the front wall of the shuttle box and shuttle respectively and feel for filling.

The shuttle 34 is provided with the usual bobbin holding jaws 36 for engaging and holding the bobbin 37 on which the filling is wound. The bobbin 37 has an inclined portion 38 which in the present instance is formed by a series of stepped cones, the cone nearest the head of the bobbin being of the greatest diameter and the successive cones gradually becoming smaller towards the tip portion of the bobbin, as indicated in Fig. 3, wherein five stepped cones are shown. Of course it will be understood that the cone stepped portion of the bobbin may be of different extent; that is, there may be a fewer or greater number of cones.

Between the head of the bobbin and the cones the bobbin has a cylindrical portion 39 and likewise at the opposite side of the cones towards the tip of the bobbin is the cylindrical portion 40 as shown in the present instance.

When a working supply of filling is present in the shuttle on a detecting beat the toothed rear end portion 41 of the feeler engages the filling, Fig. 2, and the feeler is pushed frontwardly as the lay beats up. The teeth of the feeler by engagement with the filling will hold the feeler from movement longitudinally of the filling carrier. As the weaving proceeds, however, the filling in the shuttle gradually becomes depleted until finally the inclined or stepped portion of the bobbin is presented to the end of the feeler as the lay beats up, whereupon the in-

clined surface or stepped portion of the bobbin acts against the feeler by frontward pressure to move it in a direction longitudinally of the bobbin.

- 5 When the stepped or inclined portion of the bobbin thus becomes exposed to act upon the feeler and move it longitudinally of the bobbin there may still remain a small reserve portion of the filling about the base of 10 each of the cones. This reserve supply may be sufficient to enable the shuttle to make the desired number of picks and to prevent partial picks, so that when the feeler is forced longitudinally along the bobbin by 15 the frontward pressure of the inclined or stepped portion thereof, the cloth will have been woven with full picks. The cylindrical portions of the bobbin at each side of the inclined portion are adapted to have yarn 20 wound thereon, and if desired, of course, a reserve supply of yarn may be wound on the cylindrical portion of the bobbin at either side of the stepped portion in addition to that wound on the inclined portion.
- 25 Should the surface of the bobbin be sticky or dirty and tend to retard responsive movement of the feeler longitudinally of the bobbin the inclined surface of the bobbin will act to insure movement of the feeler and 30 the consequent replenishment of filling.

Claims:—

1. In a feeler mechanism for looms, the combination of a feeler mounted for movement toward and from the front of the loom 35 and also in a direction longitudinally of the shuttle and held from such movement longitudinally of the shuttle by engagement with the filling on a detecting beat until substantial exhaustion thereof, a filling carrier contained within the shuttle and having a bobbin holding head, a cylindrical yarn holding portion adjacent the head, a second cylindrical yarn holding portion extending from the tip towards the head, and an inclined 40 portion between the two which becomes exposed when the filling is substantially exhausted and by frontward pressure of such inclined portion against the feeler on a detecting beat causes movement of the feeler in a direction longitudinally of the shuttle, and means controlled by the feeler for effecting replenishment of filling.

2. In a feeler mechanism for looms, the combination of a feeler mounted to enter the shuttle and to be displaced frontwardly 45 in a direction inclined to the longitudinal axis thereof on each detecting beat and for movement in a direction longitudinally of the shuttle and restrained from such longitudinal movement on a detecting beat by

engagement with the filling until substantial exhaustion thereof, a filling carrier supported by the shuttle and having an inclined cone portion which strikes the feeler on a detecting beat when the filling is substantially exhausted and by frontward pressure of such inclined portion causes movement of the feeler in a direction longitudinally of the shuttle, and a train of mechanism controlled by the feeler for effecting replenishment of filling.

3. In a feeler mechanism for looms, the combination of a feeler mounted to enter the shuttle in a direction inclined to the longitudinal axis thereof and for movement in a direction longitudinally of the shuttle and held from such movement by engagement with the filling on a detecting beat until substantial exhaustion thereof, a bobbin mounted in the shuttle and having cylindrical yarn receiving portions separated by an inclined yarn receiving portion which strikes the feeler on a detecting beat when the filling is substantially exhausted and by frontward pressure of the inclined portion against the feeler causes movement of the feeler in a direction longitudinally of the shuttle, and mechanism controlled by the feeler for effecting replenishment of filling.

4. In a feeler mechanism for looms, the combination of a feeler mounted to enter the shuttle in a direction inclined to the longitudinal axis thereof and displaced frontwardly in an inclined path on each detecting beat, a bobbin mounted in the shuttle and having cylindrical yarn holding portions separated by a stepped cone portion along which the feeler is moved longitudinally of the shuttle by the frontward pressure of the stepped cone portion when the filling is substantially exhausted on a detecting beat, and means set in operation by movement of the feeler for effecting replenishment of filling.

5. In a feeler mechanism for looms, the combination of a feeler mounted to enter the shuttle on each detecting beat and to be displaced longitudinally thereof by the frontward pressure upon it, a filling carrier mounted in the shuttle and having a bobbin holding head and two cylindrical filling holding portions separated by a filling holding stepped portion which becomes exposed when the filling is substantially exhausted and by frontward pressure against the feeler on a detecting beat causes movement of the feeler longitudinally of the shuttle along the bobbin.

In testimony whereof, I have signed my name to this specification.

WALLACE I. STIMPSON.
